United States Patent Office

Des. 190,085
Patented Apr. 11, 1961

190,085

SAVINGS BANK

Frederick N. Balch, North Hollywood, Calif., assignor of one-half to Emanuel E. Kotkin, Los Angeles, Calif.

Filed May 31, 1960, Ser. No. 60,782

Term of patent 14 years

(Cl. D34—5)

FIG. 1.

FIG. 2.

FIG. 3.

FIG. 4.

Figure 1 is a perspective view of a savings bank showing my new design;

The dominant features of my design reside in the portions shown in full line.

I claim:

The ornamental design for a savings bank, as shown and described.
